UNITED STATES PATENT OFFICE.

STEWART HARVEY CLARK, OF UNION CITY, INDIANA.

FINISHING WELT.

Application filed December 12, 1928. Serial No. 325,518.

My invention relates to welts, gimps and nail whereby it is secured in operative position; 5 bindings, but more particularly to finishing welts, used primarily for trimming automobiles, both upon their exterior and interior surfaces, wherever a binding or tape-like covering strip is required or desired, for 10 overlapping seams, or otherwise concealing raw edges of the trim. It is applicable also to various more or less analogous uses, such as the trimming, finishing and ornamentation of furniture for example, and is of the "blind nail" or concealed nail type of welt as exemplified by various United States patents, including that Numbered 1,226,600, is- 15 sued May 15, 1917, to Robert C. Schemmel, of Union City, Indiana.

The present invention, in its broadest sense employs a body portion or core of resilient material and of unitary formation, 20 such as rubber or other flexible substances, divided by a side kerf into a base and a flap portion capable of automatically resuming their normal close together relation after they have been momentarily deformed for 25 the passing of fastening means through the base, and in addition contemplates covering means for suitably ornamenting the core or body portion in harmonious accord with the upholstery of the automobile or other 30 vehicle in process of manufacture or repairs.

The invention therefore has for an object the production of finishing welt suitable for blind nailing consisting of two elements only, that is to say, a resilient body 35 portion or core and an enclosing cover or envelope which follows the contour of said body.

This invention has for a further object the production of a finishing welt which is 40 extremely economical in cost of manufacture, efficient in its use and operation, and attractive in appearance.

With the foregoing and other objects in view, the invention will be hereinafter particularly described and later pointed out by the claims following.

In the accompanying drawings which form part of this application for Letters Patent, and whereon corresponding numerals indicate like parts in the several views:

Figure 1 is a view in perspective of a small section of welt detached;

Figure 2 is a transverse sectional view of the welt in the process of attachment, being 55 open for reception of an attaching tack or

Figure 3 is also a transverse cross sectional view showing the welt applied; and

Figure 4 is one of many modified forms 60 of this welt detached.

Reference being had to the drawings and numerals thereon, 1 indicates the core of my improved form of welt, preferably made of rubber, quickly and cheaply extruded from 65 a suitable steel die. The core 1 however, may be made from other and any flexible material, capable of being deformed as indicated by Figure 2, for purposes of receiving fastening tacks 2, and of then automatically resuming its closed and normal 70 position, as indicated by Figure 3, thus concealing the tack 2 by which secured.

The body of the welt, as clearly shown in the accompanying drawings, comprises a 75 core kerfed at one side to provide a base portion 3, merging into a continuous overlying flap 4 of unitary construction, having at the bottom of the kerf where these two portions intersect a longitudinal continuous pocket 5 designed and adapted to facilitate the hinging of flap 4 upon base 3.

An outer covering 6 for the body 1 is provided, which follows the surface configuration of elements 3 and 4, completely 80 enveloping them as shown, and this covering may be of leather, imitation leather, or of any suitable fabric best suited to harmonize with upholstery of the vehicle, or for the particular job upon which the welt 90 is to be used.

In one embodiment of the invention, as shown by Figures 1, 2 and 3 of the drawings, a relatively small longitudinal and continuous side bead 7 is employed adjacent 95 to which the overlapping and tack concealing flap 4 abuts when in its closed and normal position as shown.

The said flap 4 may obviously be of any desired cross sectional form. It may be 100 merely a flat flap doubled upon a base 3 of like form, or preferably of a half round shape as shown, but in any event connected at one longitudinal edge which constitutes a hinge element, to permit lifting the flap 4 during introduction of the fastening tacks 2.

This being substantially the construction of my invention, its use and operation are 110 so self-evident that a detailed description

thereof is hardly required. It will be noted however, that flap 4 automatically resumes its normal closed position, as indicated by Figures 1 and 3, after being forcibly lifted 5 or deformed as indicated by Figure 2, for the introduction of tacks 2, or other fastening means, and that during this operation the continuous longitudinal weakening groove 5 greatly facilitates this hinge action.

Figure 4 represents a slightly modified form of the present invention wherein the principle of operation is the same, and wherein the longitudinal bead 7 is omitted, 15 in other respects this construction being the same as that hereinbefore described.

In like manner other and various modified forms of construction will readily suggest themselves to persons skilled in the 20 art to which this invention relates, and to all such I lay claim in so far as covered by the claims hereto appended, the same as if herein shown and described.

Having thus described my invention, 25 what I now claim and desire to secure by Letters Patent is:

1. A finishing welt including a resilient core kerfed inwardly at a side thereof to provide a base and an upper flap normally 30 in closed relation but deformable to allow fastening means to be passed through the base, the resilience of the core being sufficient to cause the flap to spring back to its normally closed relation with the base and thereby cover and conceal the fastening means when said flap is released after completion of the fastening operation.

2. A finishing welt including a resilient core of unitary construction, substantially 40 half round in section and kerfed at a side thereof to provide a base and an upper flap normally in closed relation but deformable to allow fastening means to be passed through the base, the resilience of the core being sufficient to cause the flap to spring 45 back to its normally closed relation with the

base and thereby cover and conceal the fastening means when said flap is released after completion of the fastening operation.

3. A finishing welt including a resilient 50 core having a kerf entering the core from a side thereof to divide the core into a base portion and a flap portion, in combination with a covering of flexible material encasing the core, the longitudinal edges of said 55 covering being concealed within the kerf.

4. A finishing welt including a resilient core having a substantially plane bottom surface and a curved upper surface, said core being kerfed inwardly from a side 60 thereof in a plane parallel with its bottom surface whereby the core is divided into a base portion and a flap portion normally in closed relation but adapted to be spread apart for the insertion of fastening means 65 through the base portion.

5. A finishing welt including a resilient core having a substantially plane bottom surface and a curved upper surface, said core being provided with a kerf extending 70 inwardly from one side thereof in a plane substantially parallel with the bottom surface of the core, whereby the core is divided into a base portion and a flap portion, in combination with a covering of flexible material encasing the core and terminating in longitudinal edges within the kerf.

6. A finishing welt including a resilient core kerfed inwardly at a side thereof to divide the core into a base portion and a flap 80 portion, each provided with an oppositely disposed flat surface, the resilience of the core being sufficient to allow said portions to be sprung apart to enable a headed fastening tack to be passed through the base portion and then to spring together when released to cause said flat surfaces to bear against and conceal the head of said fastening tack.

In testimony whereof I affix my signature.

STEWART HARVEY CLARK.
